UNITED STATES PATENT OFFICE.

GEORGE W. PLATT, OF GREENFIELD, MASSACHUSETTS.

MACHINE FOR COATING PILLS WITH GELATINE.

SPECIFICATION forming part of Letters Patent No. 278,456, dated May 29, 1883.

Application filed March 26, 1883. (No model.)

To all whom it may concern:

Be it known that I, GEORGE WILLARD PLATT, a citizen of the United States, and a resident of Greenfield, in the county of Franklin and Commonwealth of Massachusetts, have invented a new and useful Improvement in Machines for Coating Pills with Gelatine, of which the following is a full and true specification.

10 My invention relates to that class of machines where the pills to be coated are picked up on needle-points and then dipped in a solution of gelatine or of any other desired preparation.

15 It is well known that a large proportion of the pills now used in regular practice are coated with gelatine to prevent the loss of any part of the essential qualities of the pills by evaporation or by exposure to the air, and to 20 render them less disagreeable in their administration. This was formerly a slow and tedious operation, and though recently machines have been invented to accomplish this they have generally been too complicated and expensive for common use, or they accomplish 25 the work in an imperfect manner. My machine does the work very perfectly, can be managed by a mere novice, and is so cheap as to be within the means of any country druggist.

30 The accompanying drawings illustrate my invention and form a part of this specification.

Figure 1 is a plan view of the machine. Fig. 2 is a sectional view of the machine.

35 The principal part of the machine is a shallow box of suitable height and breadth for the purpose required. The rear part, A, is provided along its inner sides with small rails, in which are cut, at equal and suitable distances, 40 gains opposite each other, in which to set the needle-bars inverted with the pills, as herein-after described.

45 B is a partitioned space in the middle of the box to receive the pills as they are cut off from the needles, having a sliding bottom to allow the pills to be removed. C, at the front end of the box, is a shallow tray for holding the pills to be coated. This is made with an incline toward the middle of the box, so that 50 pills laid upon it will roll down to the back of the tray, which is a serrated block, D, extend-

ing the whole width, and being equally divided by notches extending through the depth of the block, which, for convenience in working merely, I usually make ten in number, though 55 that is entirely immaterial. As these notches open up the incline in the shape of a V, when a pill rolls into any one of them, it readily finds in the angle a fixed position, whether it be a large or a small one. It will be seen that this 60 is a very material advantage over having the pills run merely in grooves to be picked up, as in that case the pills are not securely held, and it requires a different set of grooves for every size of pills to be made, while with my 65 device every pill, large or small, finds its place and is firmly held, so that the needle strikes every one in the center. In combination with this serrated back is the needle-bar E, Fig. 2, having as many needles projecting from it as 70 there are notches, all exactly the same length, exactly the same distance apart, and all pointing exactly at the apexes of the notches in the serrated back D. While the whole box may be made of wood or metal, I propose to have 75 this needle-bar of metal, that the needles may be truthfully and securely fastened in it, so that they shall be always firm and exact in position and pointing at the center of one-grain pills. This needle-bar must be an exact fit in 80 the tray where the pills are placed, but so as as to move both easily and directly down, carrying the needles into the center of the circumference of every pill in the notches. If the pills are of larger size than one grain, a slight 85 pressure back on the needle-bar raises the points a very little, enough to touch the center of the pills, of whatever size they may be.

F is a small trough or vat, in which is the solution of gelatine or of any other desired substance. This vat has square ends to support it, but is preferably made with sloping sides for convenience in dipping the pills, saving of material, and ease of cleaning. As the gelatine should be kept warm, this vat or trough 90 can stand in a convenient sand bath or in warm water. The needle-bar, with the pills stuck on the points of the needles, is taken up and the pills gently immersed in the solution in the vat for a second, and when taken 95 out with the thinnest possible film of gelatine covering them they are given a circular wave

over the arm by a turn of the wrist, and the gelatine is instantly set. The needle-bar is then placed inverted with the pills up in the gains cut in the rails in the rear partition of the machine for the gelatine to harden. After the gelatine has become perfectly hard the next process is to cut the pills off the needles. In all methods heretofore adopted for doing this there is an incompleteness and serious defect, in this: there has always been left on the side of the pill where the needle enters a little neck or burr of gelatine, hard and sharp, which had formed on the needle as it was plunged into the gelatine a little deeper than the pill. My device for taking the pills from the needles, and at the same time cutting off this superfluous hardened gelatine smoothly from the pills, is as follows: On the side of the partitioned box B is fastened a piece of thin steel, like a knife-blade, *a*, extending across the box. Against the ends of this, on the sides of the box, are standards of a few inches in height, each having a slot on the inside running from the top to meet the edge of the blade *a*. In the slot runs another knife-blade, *b*, which shuts tightly down on the blade *a*. The blade *b* has on its edge a series of fine notches, arranged to exactly correspond with the needles, and just deep enough to shut down over them without touching them. The fixed blade *a* may also, if desired, be made with fine notches corresponding to those in the upper blade and to the needles. The needle-bar is taken from the rack where it is standing with the hardened pills, and the pills on the points of the needles are placed against the knife-edge *a*, the needles resting on it. The blade *b* is then put in place and brought down,

just touching the pills at their point of contact with the lower blade, *a*, and the notches, 40 closing down over the needle-points, cut the gelatine from all sides, and, the bar with the needles being quickly withdrawn, the gelatine adhering to the needles is taken off at the circumference of the pills, leaving them perfectly 45 round and smooth, with no burrs or rough points where the needles entered the pills, and they drop into the box B, whence they are removed by throwing out the sliding bottom. For convenience I place these blades in the 50 same box comprising the part for picking up, and also the rack at the other end for setting up the pills for hardening, though if for any reason preferred they may each and all be used separately.

55 In a machine for coating pills, I claim—

1. The tray described, having its depression inclined below a horizontal line, and terminating with a serrated strip, having vertical walls to form V-shaped abutments for the pills 60 to be coated, as set forth.
2. The notched blade or blades for cutting the pills from the needles, all substantially as shown and described.
3. The combination of the needle-bar with 65 needles, the inclined tray with serrated back, and the blades for cutting off the pills with the boxes, all substantially as described and set forth.

4. The combination, with the inclined tray 70 and needle-bar, of the serrated strip D, as and for the purpose set forth.

GEORGE WILLARD PLATT.
